 Conn., a corporation of Connecticut

Application October 3, 1936, Serial No. 103,898
 Renewed October 28, 1939

14 Claims. (Cl. 89—46)

1

This invention relates to power transmissions and more particularly to a conveyor for delivering articles from one station to another wherein a fire hazard is present at one station and in which it is desired to prevent the possibility of flame transmission between the two stations at all times, while permitting the continued passage of articles between the stations. The invention is particularly adapted to delivering ammunition aboard ship from an ammunition storage compartment to a position at the guns for use therein, although it will be understood that the invention may be adapted to other uses wherein similar conditions and problems are encountered.

It is customary in war vessels to locate the ammunition magazines or storage chambers in the lower part of the ship where the possibility of their contents being exploded by enemy projectiles is most remote. The guns which use the ammunition being situated on the upper decks of the ship, either in turrets or on deck mountings, it is necessary to provide means for conveying ammunition from the magazine to a position near the guns where it may be readily placed in the guns as needed.

Various types of conveyors have been heretofore provided for this purpose and where high rates of delivery to rapid firing guns are required, the so-called dredger type ammunition hoists have marked advantages over other types in use. Such a hoist usually comprises an endless chain conveyor which is encased in a continuous tubular hoist trunk or casing extending through the ship from the loading station in or adjacent the magazine to the unloading station adjacent the gun. This continuous hoist trunk provides a conduit which introduces the possibility of flame transmission to the magazine whenever accidental explosions occur at the gun or whenever an enemy projectile explodes in or near the hoist trunk.

In order to break this continuous path for flame travel to the magazine, it has been found necessary heretofore to deliver the ammunition in two stages by two entirely independent ammunition hoists with a transfer station where the ammunition is carried manually from the delivery end of the lower hoist to the loading end of the upper hoist. This construction, while satisfactory from the standpoint of safety of the installation and effectiveness to prevent the transmission of flare-backs to the magazine, adds considerably to the weight and cost of the installation since each of the two sections of the hoist must be provided with its own independent drive mechanism. Furthermore additional crew is re-

2

quired for handling ammunition at the transfer station, which not only increases the number of men required for each gun to be fired but presents also a retarding element in the delivery of ammunition since it introduces one more place for unavoidable human errors and delays to interfere with the intended operation of the hoist.

It is an object of the present invention to provide a conveyor particularly adapted for delivery of ammunition directly between a loading station adjacent the magazine and an unloading station adjacent the gun by which ammunition may be delivered through a continuous closed casing whereby transmission of flare-backs to the loading station may be prevented without requiring an intermediate transfer station.

It is also an object to provide a conveyor for delivering articles between two stations which are separated by a flame-proof wall having an opening at one station adjacent the conveyor and in which is incorporated means for passing articles through the opening while maintaining a flame-proof seal at all times.

A further object is to provide a loading station for a conveyor having an article passing mechanism which is actuated by a separate motor means independent of the conveyor drive mechanism.

It is also an object to provide a loading station for a conveyor in which a reciprocating article passing member is mounted adjacent a wall opening and is provided with at least one article receiving recess adapted to be alternately brought into register with the opening for receiving an article and moved to a position where the article may be transferred to the conveyor.

Further objects and advantages of the present invention will be apparent from the following description, reference being had to the accompanying drawings wherein a preferred form of the present invention is clearly shown.

In the drawings:

Fig. 1 is a diagrammatic cross section of a ship incorporating a preferred form of the present invention.

Fig. 2 is a front view of a loading station incorporating the present invention.

Fig. 3 is a fragmentary cross section on line 3—3 of Fig. 4.

Fig. 4 is a cross section on line 4—4 of Fig. 3.

Fig. 5 is a diagrammatic view showing the hydraulic circuits incorporated in the conveyor drive and control mechanism.

Referring now to Fig. 1 there is indicated diagrammatically a portion of a longitudinal section

of a war vessel having superimposed decks 10 of usual construction, the spaces between which are divided by partitions 12 into suitable compartments. Indicated at 14 is a deck gun and at 16 a revolving turret having two or more guns 18 mounted thereon in the usual fashion. Adjacent the gun 14 is mounted the delivery head 20 of a dredger type ammunition hoist 21 having a trunk 22 extending downwardly through the vessel to a compartment 24 which may be either a magazine compartment for the storage of ammunition or a handling room adjacent such a compartment and in which is located the loading end 25 of the hoist 21 together with suitable driving mechanism for the hoist. In the turret 16 is mounted a delivery head 26 of a second dredger type ammunition hoist 27 having a trunk 28 extending vertically downward to a compartment 30 similar to the compartment 24, in which is located the loading end 32 and the necessary driving mechanism for the hoist 27. The hoist trunk 28 is shown secured to the top deck 10 at the center of rotation of the turret 16 and is stationary relative to the turret although it will be understood that the ammunition hoist 27 may be mounted to revolve with the turret 16 if desired.

Referring now to Figs. 2 through 5 wherein the construction of the loading ends 25 and 32 is illustrated in detail, there is shown a casing 34 forming the lower end of the hoist trunk to which the casing 34 may be tightly sealed at the flange 36. The casing 34 serves not only to enclose the drive sprockets 40 and the hoist chain or conveyor band 38, having conveyor lugs 39, but also as a mounting for the hoist driving and control mechanism. The latter may be of any suitable construction. The form of drive mechanism and control therefor illustrated comprises a fluid motor 42 adapted to drive the sprockets 40 through a worm drive 44. A variable displacement pump 46 (see Fig. 5) and auxiliary pump 48 are driven by an electric motor 50 to supply fluid to the motor 42 through a control unit 52. The control unit 52 is constructed to control the displacement of the pump 46 and to control communication between the pump 46 and the motor 42 through conduits 54 in a manner to provide for automatically moving the hoist chain 38 through one flight whenever a starting "shot" of fluid from the auxiliary pump 48 is admitted to the device 52 through a control conduit 56.

For this purpose the control unit 52 comprises a body 41 having a cylindrical bore 43 in which is mounted a spool valve 45 for the purpose of blocking or opening the passage of oil between the conduits 54 and conduits 47. A second cylindrical chamber 49 carries a spool valve 51 for the purpose of reversing the flow between the conduits 47 and a pair of conduits 53 which lead to the fluid motor 42. The body 41 also has at its upper end a bore 55 in which is mounted a spool valve 57 for controlling the stroke regulating fluid motor of the pump 46. A conduit 59 extends from the auxiliary pump 48 to the upper end of the bore 55 while a conduit 60' enters the bore 55 at its mid-portion. The valve 57 is adapted to selectively control and reverse the connections of the conduits 59 and 60' with a pair of conduits 63 and 65 leading to opposite ends of the stroke regulating mechanism at the pump 46. The valves 45 and 57 are formed integrally upon a common stem having an enlarged portion 67 around which is slidably mounted a lift piston 69. The latter has a cylindrical upper portion 75

71 slidably fitted in a chamber 73 which communicates with the upper end of the bore 55 through a passage 75 formed in the spool of valve 57. The piston 69 has a portion 76' of larger diameter than the portion 71 and slidably fitted in a chamber 78' to which the conduit 56 leads. The bottom wall of the piston 69 is provided with an opening forming a clear passage around the stem of valve 45 and having a seat on which the enlarged portion 67 of the stem is adapted to rest for the purpose of closing this passage. The space inside the piston 76' communicates with the tank through a passage 80' formed in the stem of the valve 45. At its lower end the valve stem has a roller 82' acting as a follower for a cam 85. The latter is connected by a suitable drive means not shown to the shaft of the sprockets 40 so that the cam 85 makes one revolution while the chain 38 travels through one flight distance. The cam 85 has a depression in which the roller 82' is shown at rest. In this position the valve 45 is completely closed while the valve 57 connects the conduit 63 to the pressure line 59 and the conduit 65 to the tank line 60'. To either side of this depression are elevated portions 87 which hold the valves in such a position that the valve 45 is opened to a considerable degree while the valve 57 still connects conduit 63 with the conduit 59 and conduit 65 with conduit 60'. The remainder of the periphery of the cam 85 is raised still further so as to completely open the valve 45 and to reverse the connections at the valve 57. When the valves are raised to this upper extreme position the valve stem has been lifted higher than it is possible to lift the piston 69, so that the enlarged portion 67 lifts away from the seat in the bottom wall of the piston 69. The cam 85 and its drive mechanism are enclosed in a suitable oil-tight housing not shown, the interior of which is connected to tank.

The entire arrangement of the control unit 52 is such that whenever a shot of oil is admitted through the conduit 56 to the chamber 78', the piston 69 is lifted due to the enlarged portion 67 being on its seat in the bottom wall of the piston 69. The piston 69 and both valves 45 and 57 are accordingly lifted to a position just short of the highest position to which the cam would lift them. Thus the valve 45 is opened and the valve 57 is reversed to cause the stroke of the pump 46 to be increased at a rate determined by the volumetric capacity of the auxiliary pump 48. Oil is delivered to and returned from the fluid motor 42 through the conduits 54, 47, and 53, thus causing the motor 42 to operate, turning the cam 85. The latter will contact the roller 82' after about one-quarter of a revolution when the highest part of the cam strikes the roller 82', thus lifting the valves 45 and 57 a further amount. This additional lift raises the enlarged portion 67 off from the seat in the bottom wall of the piston 69, thus permitting the oil trapped in the chamber 78' to escape through the opening in the bottom wall of the piston 69 and through the passage 81 to tank. As soon as the cam has completed an approximate one-half revolution in addition, the roller 82' drops down to the cam portion 87, thus reversing connections at valve 57 but not completely closing the valve 45. The stroke of the pump 46 is thus reduced at a rate determined by the capacity of pump 48 causing the motor 42 to decelerate. When the cam 85 has completed a revolution, the roller 82' returns to the position shown in the drawings, completely closing the valve 45. At this time the enlarged

portion 67 again comes to rest on its seat in the bottom wall of piston 69, thus placing the apparatus in condition for restarting whenever another shot of oil is introduced to the conduit 56. It will be noted that should a shot of oil be introduced to the conduit 56 before the cam 85 has made one revolution, the lift piston 69 will not rise because a free path is opened from the chamber 78' to tank through the passage in which the enlarged portion 67 seats. It will also be noted that oil pressure from the auxiliary pump is constantly exerted over the upper end of the valve 57 creating a bias for the entire stem assembly in the downward direction. Likewise this pressure is exerted over the annular area at the top of the portion 71 of the lift piston 69 biasing the latter downwardly whenever pressure is relieved in the chamber 78' by the opening of the passage through the bottom wall of the piston 79.

The casing 34 is provided on its front face with an outward extension 58 having a pair of openings 60 and 61 of proper size and shape to permit a piece of ammunition to pass therethrough. The extension 58 is hinged to the casing 34 at 62 along one edge thereof and is adapted to be clamped in sealing engagement therewith by suitable securing means 64. The extension 58 is formed with a chamber 66 in which is mounted a reciprocating carrier member 68 which forms a pair of adjacent recesses 70 and 72. For this purpose the carrier 68 is formed with a bottom wall 74 and a similar top wall, not shown, and with three vertical walls 76 forming the sides of the chambers 70 and 72. The width of the chambers 70 and 72 and the spacing of the openings 60 and 61 are such that the carrier 68 may be reciprocated between the position shown in Fig. 4 in which the recess 70 is opposite the opening 60 and a position to the left thereof in which the recess 72 is opposite and in register with the opening 61.

Intermediate the openings 60 and 61 in the back wall of the chamber 66 is formed an opening 78 opposite the hoist chain 38 and with which either of the recesses 70 and 72 may register when the other is in register with an opening 60 or 61. A pair of flapper doors 77 are pivoted in the casing 34 at the sides of the opening 78 and are spring biased to closed position and adapted to be opened at certain times by trip levers 79 lying in the path of lugs 39. Bevel gearing 81 connects the trip levers 79 to the pivot shafts of the flapper doors 77. A lost motion drive connection at 83 permits the trip levers 79 to be moved downwardly without actuating the doors 77 during lowering operation of the hoist.

In front of the carrier 68 there is reciprocably mounted a sliding door 80 of proper width to close one of the openings 60 or 61 while leaving the other open. The carrier 68 and the door 80 each carry rigidly secured thereto downwardly extending pins 82 and 84 respectively which project through slots 86 and 88 formed in the bottom wall 90 of the extension 58. A lever 92 is pivoted to the wall 90 on the lower side thereof embracing at its outer ends the pins 82 and 84 whereby the carrier 68 and the door 80 are caused to move simultaneously in opposite directions. The pin 82 extends below the lever 92 to enter a bore formed in an operating piston 94 which is reciprocably mounted in a pair of cylinders 96. The cylinders 96 are formed integrally with a cover plate 98 which is removably secured to the bottom wall 90 to cover the mechanism attached thereto. Also formed integrally in the cover 98

are a pair of directional control valves 100 and 102. The movable elements of valves 100 and 102 are mounted on a common stem 104 which is connected by a fork and collar connection to a snap action lever 106. The latter is pivoted coaxially with the lever 92 and connected to be operated thereby through a spring 108 to provide snap movement of the lever 106 as the lever 92 reaches either end of its oscillation.

10 Mounted on the casing 34 behind a back wall 110 of the chamber 66 are a pair of carrier trip valves 112 and 114. Each of these valves is connected for operation by a trip lever 116 and 118, respectively, each of which has a portion projecting into the chamber 66 and into the recesses 70 and 72 when opposite one of the openings 60 and 61. The trip levers 116 and 118 are adapted to be moved counterclockwise in Fig. 3 whenever a piece of ammunition is properly placed in a recess 70 or 72. Pivotedly mounted in the casing 34 adjacent the lower edge of the opening 78 at 120 is a lower trip lever 122 adapted to be depressed by a piece of ammunition such as 124 when it is placed in position on the hoist chain 38. The lower trip 122 is connected by an arm 126 (see Fig. 5) to a lower trip valve 128 mounted in a valve block 130. An upper trip valve 132 is also mounted in the block 130 and is adapted to be actuated by solenoid 134 which in turn is controlled by an upper trip 136 located at the delivery end of the hoist.

The valve 128 is adapted to connect a conduit 138 with a conduit 140 when the trip 122 is depressed and to connect with a conduit 142 when the trip 122 is raised. The valve 132 is adapted to open communication between the conduit 140 and the conduit 56 whenever the solenoid 134 is energized and to close communication when the solenoid is deenergized. The solenoid 134 is under the control of the upper trip 136 through a three-way switch 144 which is connected in circuit with a three-way switch 146 adapted to be actuated by a reversing lever 148. When the reversing lever 148 is set to hoist ammunition, as illustrated in Fig. 5, the switch 146 connects the solenoid to the switch 144 so that the solenoid will be energized from the source 145 whenever the trip 136 is released by removal of ammunition from the delivery end of the hoist. With the reverse lever 148 set for lowering ammunition, the switch 146 connects the switch 144 for opposite action.

The lever 148 also controls a reversing valve 150 for selectively connecting conduit 138 or the conduit 142 with a conduit 152 leading from the auxiliary pump 48, as well as controlling valve 51 for reversing the operation of the motor 42. The valve 150 also connects the conduits 138 and 142 with drain conduits 151 and 153 when not connected to conduit 152. The carrier trip valves 112 and 114 are connected by conduits 156 to a lower trip relay valve 158 which is adapted to close communication between the conduits 156 and a branch 160 of conduit 152 whenever lower trip valve 128 admits fluid to the conduit 140. For this purpose a conduit 162 extends from the conduit 140 to the left-hand end of the relay valve 158 for admitting pressure fluid to the end surface of a large piston 164. The large piston 164 is connected by a stem 166 to a small piston 168, the space to the right of which is connected to the expansion tank 170 through a conduit 172.

The large piston 164 when in the position illustrated blocks communication between conduits

160 and 156. When the piston 164 moves to the left due to the release of pressure fluid in the conduit 140, communication is established between the auxiliary pump 49 and the carrier trip valves 112 and 114 through conduits 152, 160, and 156. Each of the valves 112 and 114 comprise a piston valve 174 adapted to open communication between the conduit 156 and a conduit 176 leading to the corresponding directional control valve 100 or 102, whenever the trip lever 116 or 118 is depressed by a piece of ammunition lying in one of the recesses 70 or 72. A pressure operated holding valve 178 is also mounted in each valve block 112 and 114 and is moved to the right in Fig. 5 whenever fluid pressure is admitted through the valve 174 to the conduit 176. This movement opens communication between the conduit 176 and conduit 156 through a parallel path including a restrictive conduit 180 so that when fluid pressure is once admitted to the conduit 176 by the opening of valve 174, the pressure is maintained therein through the valve 178 so long as there is any existing back pressure at the remote end of the conduit 176. The valves 100 and 102 are adapted to selectively connect a cylinder 96 either with a conduit 176, as shown in Fig. 5, or to connect both a cylinder 96 and a conduit 176 with the expansion tank 170 through a branch 182 of the conduit 172.

In operation with the motor 50 and pumps 46 and 48 running and with the hoist at rest due to the presence of a piece of ammunition at the delivery station, the trip 136 keeps the solenoid 134 deenergized so that fluid from the pump 48 is blocked off from the conduit 56 at the valve 132. Assuming a piece of ammunition to have been dropped from the recess 72 by the flapper doors 77 and to lie on the chain 38 and the lower trip 122, as illustrated in Fig. 5, as soon as the ammunition is removed from the delivery station trip 136 is released to energize solenoid 134, opening valve 132 to admit pressure fluid to the conduit 56. The control unit 52 in response to the admission of pressure fluid to the conduit 56 causes the fluid motor 42 to drive the sprockets 40 and chain 38 through one flight; that is, through the distance to bring the next lug 39 into rest position, as illustrated in Fig. 5.

Assuming a piece of ammunition to have been placed in the recess 70 through the opening 60 before the start of the hoist cycle, the trip 116 will be depressed so that valve 174 will be open. With the piston 94 and the valve 100 lying in the position illustrated in Fig. 5, the piston 94 will not be actuated at the beginning of the cycle until the lug 39 has picked the ammunition off from the lower trip 122 and permitted the latter to raise, thus transferring the conduit 148 from the pressure line 138 to the drain line 142. As soon as this occurs the lower trip relay valve 158 moves to the left admitting pressure fluid from the conduit 160 to the conduit 156. The piston 94 is thereby caused to move to the left in Fig. 5 moving the carrier 68 to the left and through the lever 92 moving the door 80 to the right in Fig. 4. This action once started is continued regardless of the release of trip 116 as the ammunition moves to the left away from the same because the holding valve 178 opens a connection around the valve 174 through the passage 180. When the piston 94 completes its movement to the left, the recess 70 is opposite the flapper doors 77 and the recess 72 is opposite the opening 61. Near the end of the flight the next lug 39 actuates the trip levers 79 to open the

doors 77 and the ammunition in the recess 70 accordingly drops on to the chain 38 and lower trip 22 is ready for the next cycle of operation. At the end of the movement of piston 94 the snap acting lever 106 is operated to shift the valves 100 and 102 connecting the left-hand cylinder 96 to valve 114 and connecting the right-hand cylinder 96 to the drain conduit 182. The holding valve 178 is thereby permitted to move to the left again closing the by-pass 180 until such time as pressure fluid is again admitted to the conduit 176.

While the form of embodiment of the invention as herein disclosed constitutes a preferred form, it is to be understood that other forms might be adopted, all coming within the scope of the claims which follow.

What is claimed is as follows:

1. In a conveyor for delivering ammunition between a loading station adjacent a storage compartment and a station for use and having an endless flexible ammunition conveyor band, a flame-proof casing surrounding the conveyor band and means for driving the conveyor band, the combination with the conveyor of means for passing ammunition into said casing at the loading station and separate motor means for driving the ammunition passing means, whereby the ammunition passing means may be operated while the conveyor is stationary.

2. In a conveyor for delivering ammunition between a loading station adjacent a storage compartment and a station for use and having an endless flexible ammunition conveyor band, a flame-proof casing surrounding the conveyor band and means for driving the conveyor band, the combination with the conveyor of means for passing ammunition into said casing at the loading station, separate motor means for driving the ammunition passing means, and means responsive to the positioning of a piece of ammunition on the conveyor for controlling operation of said motor.

3. In a conveyor for delivering ammunition between a loading station adjacent a storage compartment and a station for use and having an endless flexible ammunition conveyor band, a flame-proof casing surrounding the conveyor band and means for driving the conveyor band, the combination with the conveyor of means for passing ammunition into said casing at the loading station, separate motor means for driving the ammunition passing means, and means responsive to positioning of a piece of ammunition in the ammunition passing means for controlling operation of said motor.

4. In a conveyor for delivering ammunition between a loading station adjacent a storage compartment and a station for use and having an endless flexible ammunition conveyor band, a flame-proof casing surrounding the conveyor band and means for driving the conveyor band, the combination with the conveyor of means for passing ammunition into said casing at the loading station including a linearly reciprocable carrier having an ammunition receiving recess, and means cooperating with the ammunition passing means for maintaining a flame-proof seal between the inside and outside of the casing at all times whereby the transmission of flare-backs from the use station to the loading station is prevented.

5. In a conveyor for delivering ammunition between a loading station adjacent a storage compartment and a station for use and having an

endless flexible ammunition conveyor band, a flame-proof casing surrounding the conveyor band and means for driving the conveyor band, the combination with the conveyor of means for passing ammunition into said casing at the loading station including a linearly reciprocable carrier having an ammunition receiving recess, means cooperating with the ammunition passing means for maintaining a flame-proof seal between the inside and outside of the casing at all times whereby the transmission of flare-backs from the use station of the loading station is prevented, and separate motor means for driving the ammunition passing means.

6. In a conveyor for delivering ammunition between a loading station adjacent a storage compartment and a station for use and having an endless flexible ammunition conveyor band, a flame-proof casing surrounding the conveyor band and means for driving the conveyor band, the combination with the conveyor of means for passing ammunition into said casing at the loading station, and means including an alternately reversing fluid motor for driving the ammunition passing means.

7. In a conveyor for delivering ammunition between a loading station adjacent a storage compartment and a station for use and having an endless flexible ammunition conveyor band, a flame-proof casing surrounding the conveyor band and means for driving the conveyor band, the combination with the conveyor of means for passing ammunition into said casing at the loading station including a reciprocable carrier having an ammunition receiving recess, means cooperating with the ammunition passing means for maintaining a flame-proof seal between the inside and outside of the casing at all times whereby the transmission of flare-backs from the use station to the loading station is prevented, and means including a reciprocating piston motor for reciprocating said carrier.

8. In a conveyor for delivering articles between two stations the combination of an endless flexible conveyor band, means for driving said conveyor band, means forming a flame-proof wall between said conveyor band and one of said stations, said wall having an opening adjacent the conveyor band through which articles may pass, means associated with said opening for passing articles therethrough and cooperating with said opening for maintaining said opening sealed against the passage of flame, and separate motor means for driving the article passing means.

9. In a conveyor for delivering articles between two stations the combination of an endless flexible conveyor band, means for driving said conveyor band, means forming a flame-proof wall between said conveyor band and one of said stations, said wall having an opening adjacent the conveyor band through which articles may pass, means associated with said opening for passing articles therethrough and cooperating with said opening for maintaining said opening sealed against the passage of flame, separate motor means for driving the article passing means, and means responsive to the positioning of an article on the conveyor for controlling operation of said motor.

10. In a conveyor for delivering articles between two stations the combination of an endless flex-

ible conveyor band, means for driving said conveyor band, means forming a flame-proof wall between said conveyor band and one of said stations, said wall having an opening adjacent the conveyor band through which articles may pass, means associated with said opening for passing articles therethrough and cooperating with said opening for maintaining said opening sealed against the passage of flame, separate motor means for driving the article passing means, and means responsive to the positioning of an article in the article passing means for controlling operation of said motor.

11. In a conveyor for delivering articles between two stations the combination of an endless flexible conveyor band, means for driving said conveyor band, means forming a flame-proof wall between said conveyor band and one of said stations, said wall having an opening adjacent the conveyor band through which articles may pass, means including a linearly reciprocable carrier having an article receiving recess associated with said opening for passing articles therethrough and cooperating with said opening for maintaining said opening sealed against the passage of flame, and means for driving the article passing means.

12. In a conveyor for delivering articles between two stations the combination of an endless flexible conveyor band, means for driving said conveyor band, means forming a flame-proof wall between said conveyor band and one of said stations, said wall having an opening adjacent the conveyor band through which articles may pass, means associated with said opening for passing articles therethrough and cooperating with said opening for maintaining said opening sealed against the passage of flame, and means including an alternately reversing fluid motor for driving the article passing means.

13. In a conveyor for delivering articles between two stations the combination of an endless flexible conveyor band, means for driving said conveyor band, means forming a flame-proof wall between said conveyor band and one of said stations, said wall having an opening adjacent the conveyor band through which articles may pass, means including a reciprocable carrier having an article receiving recess associated with said opening for passing articles therethrough and cooperating with said opening for maintaining said opening sealed against the passage of flame, means for driving the article passing means, and means including a reciprocating piston motor for reciprocating said carrier.

14. In a conveyor for delivering articles between two stations the combination of an endless flexible conveyor band, means for driving said conveyor band, means forming a flame-proof wall between said conveyor band and one of said stations, said wall having an opening adjacent the conveyor band through which articles may pass, means including a linearly reciprocable carrier having an article receiving recess associated with said opening for passing articles therethrough transversely to the reciprocation of the carrier and cooperating with said opening for maintaining said opening sealed against the passage of flame, and means for driving the article passing means.

RALPH L. TWEEDALE.

Certificate of Correction

Patent No: 2,403,886.

July 9, 1946.

RALPH L. TWEEDALE

It is hereby certified that errors appear in the printed specification of the above numbered patent requiring correction as follows: Column 5, line 19, for "piston 79" read *piston 69*; column 9, line 54, claim 8, after "passing means" and before the period insert the comma and words, *whereby the ammunition passing means may be operated while the conveyor is stationary*; and that the said Letters Patent should be read with these corrections therein that the same may conform to the record of the case in the Patent Office.

Signed and sealed this 29th day of October, A. D. 1946.

[SEAL]

LESLIE FRAZER,

First Assistant Commissioner of Patents.
